UNITED STATES PATENT OFFICE.

JOHN JOSEPH PINDAK, OF CHICAGO, ILLINOIS.

ARMOR.

SPECIFICATION forming part of Letters Patent No. 700,082, dated May 13, 1902.

Application filed August 1, 1901. Serial No. 70,503. (No model.)

To all whom it may concern:

Be it known that I, JOHN JOSEPH PINDAK, a citizen of the United States, and a resident of Chicago, in the county of Cook and State 5 of Illinois, have invented a new and Improved Armor, of which the following is a full, clear, and exact description.

The object of the invention is to provide a new and improved armor for the sides of war 10 and other vessels, turrets, and other devices to be protected against projectiles, the armor being simple and durable in construction, readily applied or removed, and arranged to break the force of the projectile and to equalize and distribute the blow or impact over a 15 large area, thus applying the greatest resistance to the penetrating power of the projectile and preventing the latter from breaking or rupturing the armor.

20 The invention consists of novel features and parts and combinations of the same, as will be fully described hereinafter and then pointed out in the claims.

A practical embodiment of the invention is 25 represented in the accompanying drawings, forming a part of this specification, in which similar characters of reference indicate corresponding parts in all the views.

Figure 1 is a cross-section of the improvement on the line 1 1 in Fig. 3. Fig. 2 is a 30 similar view of the same on the line 2 2 in Fig. 3. Fig. 3 is a sectional plan view of the same. Fig. 4 is an edge elevation of one of the armor-plates, and Fig. 5 is a perspective 35 view of one end of an armor-plate.

The improved armor consists, essentially, 40 of armor-plates A A' A², fitted one alongside the other and abutting at their ends to produce an unbroken area, and each plate is provided at its ends with inwardly-projecting spaced and parallel spring-arms B, extending 45 beyond the ends of the plate, as is plainly indicated in Figs. 3, 4, and 5. Each of the arms B has a foot B', resting on a chair C, bolted, riveted, or otherwise secured to a steel foundation D, secured to or forming part of the side of the vessel or other device on which armor is to be used. Each chair C is provided with slotted lugs or guideways C' between 50 each foot B' of an armor-plate, and through the several slotted lugs or guideways extends a key E, also extending through a transverse

groove B², formed on the outer faces of the feet B', as will be readily understood by reference to Figs. 2 and 3. By this arrangement 55 the foot of each spring-arm B is guided in the direction of the length of the spring-arms, and in case a projectile strikes a plate the spring-arms yield and the keys E guide the feet of the spring-arms in a longitudinal direction. 60 It is understood that in case a projectile strikes the armor-plate the impact thereof causes the plate to yield, the spring-arms extending in opposite directions and returning as soon as the plate is relieved of the pressure, so that the several parts again assume 65 their normal position, as shown in the drawings.

From each foot B' of a spring-arm extends 70 upwardly or outwardly an extension-arm B³, terminating in a transversely-grooved head B⁴, resting on the rear or inner face of the next adjacent plate, the contact-point being about one-third the length of a plate from the edge thereof, as will be understood by reference to Fig. 3. A key F engages the several 75 grooves of the heads B⁴, and this key is held to slide in guideways G, formed or secured to the rear or inner side of the corresponding armor-plate, the action of the key F and 80 guideway G being the same as that of the key E in the guideway C'.

By the construction described the spring-arms of each armor-plate are approximately 85 U-shaped, with a portion resting on the chairs C and the other remaining portion supporting adjacent armor-plates, the spring-arms supporting the said armor-plates a distance 90 from the side foundation D to form an air-cushion for the armor-plates. It will further 95 be evident by reference to Fig. 3 that each armor-plate has its spring-arm resting on the said foundation D, and each armor-plate is in addition supported by the extension-arms of adjacent armor-plates, so that a very firm support for each armor-plate is obtained. The arms of adjacent plates are arranged to 100 interlock, as will be readily understood by reference to Fig. 2, to give the desired support to the arms for properly supporting the armor-plates, said interlocking arms also preventing displacement of a plate.

The entire armor-plate can be readily attached to the side of any vessel, turret, or

other device and can also be easily detached whenever desired by withdrawing the several keys E and F and leaving the plates out of position.

5 Having thus fully described my invention, I claim as new and desire to secure by Letters Patent—

1. Armor comprising plates each having yieldable arms which have bearing against a suitable backing and against adjacent armor-plates, as and for the purposes set forth.

2. An armor, comprising armor-plates, and spring-arms thereon, projecting inwardly to rest on the side of the vessel and thereby 15 yieldingly support an armor-plate and form an air-cushion for the same, each spring-arm also forming a support for an adjacent armor-plate, as set forth.

3. An armor, comprising armor-plates having their ends provided with integral spring-arms extending inwardly, and chairs on which the spring-arms are slidably held, as set forth.

4. An armor, comprising armor-plates having their ends provided with integral spring-arms extending inwardly, and chairs on which 25 said spring-arms are slidably held, said arms having extensions for supporting the next adjacent armor-plate a distance from the end thereof, as set forth.

30 5. An armor, comprising armor-plates each having inwardly-projecting spring-arms at each end, each spring-arm being formed with

a foot and an extension having a head, chairs and keys for receiving and holding the feet of the spring-arms, and keys and guideways 35 on the armor-plates for receiving the grooved heads of the spring-arms of an adjacent plate, as set forth.

6. Armor comprising plates each having yieldable arms disposed in crossing relation, 40 means for movably confining said arms against a suitable backing, and means whereby the arms of one plate are movably connected with an adjacent plate or plates.

7. Armor comprising plates each having a 45 series of yieldable arms which are fashioned to produce thereon two points of bearing, one of which points of each arm engages with a suitable backing and the other point of bearing engaging with an adjacent armor-plate. 50

8. Armor comprising plates each having yieldable arms disposed in crossing relation to arms on adjacent plates, a suitable foundation or backing, means for slidably holding said arms on the foundation, and other means 55 for loosely confining the free ends of said arms on the rear sides of the armor-plates.

In testimony whereof I have signed my name to this specification in the presence of two subscribing witnesses.

JOHN JOSEPH PINDAK.
